UNITED STATES PATENT OFFICE.

RICHARD MILLER AND JOHN GEORGE KANOUSE, OF APPLETON, WISCONSIN,
ASSIGNORS TO THE EAGLE MANUFACTURING COMPANY, OF SAME PLACE.

DOOR-HANGER.

SPECIFICATION forming part of Letters Patent No. 402,342, dated April 30, 1889.

Application filed December 27, 1888. Serial No. 294,768. (No model.)

To all whom it may concern:

Be it known that we, RICHARD MILLER and JOHN GEORGE KANOUSE, citizens of the United States, residing at Appleton, in the county of Outagamie and State of Wisconsin, have invented certain new and useful Improvements in Door-Hangers, of which the following is a specification, reference being had therein to the accompanying drawings, in which—

- 10 Figure 1 represents a front elevation of our improved door-hanger complete; Fig. 2, an end elevation of the same, the door, rail, and support being in section; Fig. 3, a plan view of the parts attached to the door; Fig. 4, a detail 15 perspective view of the combined axle bar and brace; Fig. 5, a front view of one of the rail-supports; Fig. 6, a detail sectional view showing the rail-support and manner of adjustably securing the rail thereto, and Fig. 7 20 a slight modification of the rail-support.

The invention has relation particularly to that class of door-hangers wherein two or more brackets or hangers are bolted to the upper edge of the door, each of these brackets having two horizontal axle bars or rails, which rest upon the projecting ends of the axles of interposed wheels or rollers, the wheels or rollers being adapted to rest and travel upon a stationary rail secured to the adjacent 25 building or other support, as will be more fully hereinafter set forth.

The essential and primary object of this invention is to provide improved and simplified means for supporting the rail and attaching it to its supports, whereby the said rail-supports may be readily placed at any points or positions along the length of the rail (as the exigencies of the case may require) without boring or drilling holes in the rail or otherwise weakening it, as will presently appear.

The invention has also for its object the production of a simple and very strong hanger or bracket to be attached to the upper edge of the door, as will more fully hereinafter appear.

Referring to the annexed drawings by letter, A designates a portion of a sliding door of any description.

B designates the hanger or bracket bolted 50 to the door.

C designates the adjacent portion of a barn or other building; D, the vertical battens secured thereon, and E the rail secured to the barn or other support, C. The rail E may be of any suitable length, and is preferably constructed of a bar of plain angle-iron, as shown in Figs. 2 and 6, without holes or notches of any kind. The rail is supported upon tubular spacing or supporting blocks or castings F, these blocks being provided with notches 55 in their outer ends for the reception of the lower edge of the rail. The rails are adjustably secured to the blocks and the blocks to the support or barn by means of horizontal bolts a, located immediately below the lower 60 edge of the rail, the bolts passing preferably through the tubular blocks and the adjacent portion of the building C and battens D, as shown clearly in Fig. 6, and provided on their inner ends with suitable tightening-nuts. By 65 thus notching the outer ends of the spacing-blocks for the reception of the rail it will be observed from Fig. 6 that the head a' of the bolt a may be made to bear directly upon the outer surface of the rail and the outer end of 70 the block, thus insuring a rigid attachment of the rail. It will also be observed that the rail may be readily adjusted endwise by simply loosening the nut upon the bolt.

In lieu of the angle-iron rail shown in Figs. 2 and 6, we may employ a plain flat bar-rail, as shown in Fig. 7; but we prefer the angle-iron, inasmuch as a greater degree of strength with a lesser amount of metal may be obtained by using that form of rail.

In all the methods of supporting the rails heretofore used, in connection with door-hangers, it has been necessary to drill holes through the rails for the passage of the securing bolts and rivets. This method of attaching and supporting the rails is obviously imperfect and defective, inasmuch as the rails will be considerably weakened transversely, and will consequently have to be made much larger and heavier, especially for 95 the support of heavy doors. And then again, as it is impossible to know just at what points along the rails the holes will be needed, (as the spaces between the battens vary greatly,) the manufacturer has to drill holes a short 100

distance apart along the entire length of the rail, thus weakening the rail to a very serious extent. It is obvious that the drilling of the holes cannot be left for the consumer or pur-
5 chaser. By our invention these and other serious drawbacks which attend the use of the ordinary method of supporting the rails are completely obviated.

Our invention permits the rail to be readily
10 adjusted endwise, either way and to any ex-
tent, and it also allows the spacing-blocks to
be placed at any desirable points along the
entire length of the rail, wherever the battens
may occur. It is also obvious that at any
15 time after the rail is secured in place, should
it sag or become weakened at any point, an
additional supporting-block and bolt may be
readily attached at the weak point without
disturbing any of the parts.

20 The hangers may be constructed in any
approved manner, but in this instance they
are each constructed as follows: Two vertical
bars of iron, *b b*, form the main frame of the
hanger, and are suitably bolted to the door
25 near the upper edge of the same. The upper
portions of these two bars are curved or turned
inwardly and downwardly, forming arches or
hooks *b' b'*. Bolted or riveted to these bars
b, one to the main portions and the other to
30 the end of the arched or bent portions, are
the two horizontal parallel axle-bars *c c*, the
lower edges of these bars being arranged in
the same horizontal plane. The under or
lower edges of the axle bars or rails rest upon
35 the projecting ends of the axle of the grooved
wheel or roller *G*, which latter travels upon
the rail *E* and works freely back and forth
between the axle-rails as the door is operated.

40 The ends of the inner bar, *C*, are extended
out a short distance and turned outwardly,
as at *c'*, and then downwardly, terminating
in depending portions *c''*, as shown most
clearly in Fig. 4. By thus constructing the
45 hanger it will be very strong and durable, its
strongest points being where the most strain
is usually brought to bear. The depending
portions *c''* may be bent in toward each

other a short distance and bolted to the face
of the upright bars *b*, the same bolts that se-
cure these latter bars to the door being used
50 to secure the said depending portions, as
shown in Fig. 1. Of course it is evident that
the portions *c''* may be made longer, if desired
or found necessary in hanging heavy doors.
By thus bolting the portions *c''* upon the face
55 of the upright bars the latter are greatly
strengthened and re-enforced.

Having thus fully described our invention,
what we claim as new, and desire to secure by
Letters Patent, is—
60

1. The combination, with a suitable sup-
port, of a rail, spacing and supporting blocks
interposed between the rail and support, and
headed bolts for securing the said rail to the
faces of the outer ends of the said block, the
65 said bolts passing below the lower edge of the
rail and into the said support, whereby the
rail and spacing-blocks may be adjusted in-
dependently of each other, substantially as
described.
70

2. The combination of the vertical bars *b*
b, having their upper ends bent over, forming
arches *b' b'*, the horizontal rails *c c*, se-
cured to upper ends of the said bars, the
inner one of the said rails being extended
75 outwardly and downwardly and bolted to the
said vertical bars *b b*, whereby the said ver-
tical bars and their arches are effectually
braced and strengthened.

3. The combination of a suitable support,
80 a rail, tubular spacing-blocks interposed be-
tween the said rail and support, these spacing-
blocks being notched at their outer ends for
the reception of the lower edge of the rail,
and headed bolts for holding the said rails in
85 their notches and clamping the spacing-blocks
to their support, as described.
70

In testimony whereof we affix our signatures
in presence of two witnesses.

RICHARD MILLER.

JOHN GEORGE KANOUSE.
